CLAIM

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view of the cellular phone in an opened state;

FIG. 9 is a front view in an opened state thereof;

FIG. 10 is a rear view in an opened state thereof;

FIG. 11 is a left side view in an opened state thereof;

FIG. 12 is a right side view in an opened state thereof;

FIG. 13 is a top view in an opened state thereof; and,

FIG. 14 is a bottom view in an opened state thereof.

The broken lines shown in the drawings illustrate portions of the cellular phone that form no part of the claimed design.

1 Claim, 10 Drawing Sheets
